STRETCHING MACHINE JAW

Mose D. Ripley, Hawthorne, Calif., assignor to
North American Aviation, Inc., Inglewood,
Calif., a corporation of Delaware

Application August 7, 1942, Serial No. 453,921

1 Claim. (Cl. 24—248)

My invention relates generally to a hydraulically operated machine for stretching and shaping metal sheets, and more particularly my invention relates to improvements in jaws used on such a machine.

It is an object of my invention to provide such a jaw that will grip sheet metal for a straight pull, in a variety of positions of the jaw.

Still another object is to provide a jaw for such a machine that will minimize the tearing of sheet metal adjacent the jaw.

My invention also has for its objects to provide a jaw for such a machine that is positive in operation, convenient in use, easily operable to grip sheet metal and easily operable to release such sheet metal, economical of manufacture, relatively simple and of general superiority and serviceability.

The invention also comprises novel details of construction and novel combinations and arrangements of parts, which will more fully appear in the course of the following description. However, the drawings merely show and the following description merely describes one embodiment of the present invention, which is given by way of illustration or example only.

In the drawings, like reference characters designate similar parts in the several views.

Fig. 1 is a diagrammatic elevational view of a pair of jaws mounted in relative operative positions.

Fig. 2 is a slightly enlarged side elevation, partly broken away, looking in the direction of arrows 2—2 of Fig. 1.

Fig. 3 is an enlarged section taken on line 3—3 of Fig. 2.

Fig. 4 is an enlarged section taken on line 4—4 of Fig. 2.

Fig. 5 is a broken section of the lower portion taken on line 5—5 of Fig. 2.

Fig. 6 is an enlarged longitudinal section, broken away, taken on line 6—6 of Fig. 1.

Referring more in detail to the drawings, the reference numeral 7 generally designates heavy parallel beams comprised in the machine. Mounted upon these beams 7, by means of T-headed bolts 8 are journals 9. Nuts 10 are screwed on the threaded ends of the bolts 8, to clamp the journals 9 in position on the beams 7 of the machine. A washer 12 is shown between the nut 10 and journal 9.

The journals 9 have ears 13 for journaling a shaft 14 parallel with each of the beams 7.

Jaw bodies 15 are pivoted upon the shafts 14 in the lower portion of such jaw bodies. The full 55

line and dotted line positions of the jaw body 15, in Fig. 3, illustrate different pivoted positions. The inner faces 16 and 17 of the jaws 18 and 19 on the jaw body 15, converge toward lips 20 and 21 of the jaws 18 and 19 respectively. Liners 22 and 23 are disposed upon the converging faces 16 and 17 of the jaws. Mounted upon the liners 22 and 23 are converging series of roller bearings 24 and 25.

Arranged upon said roller bearings are movable clamping plates 26 and 27. These plates have guide pins 28 to direct converging movement of the plates on the roller bearings. Upon the faces of the plates 26 and 27, are replaceable inserts 29 and 30. The inserts 29 and 30 may be suitably knurled or roughened as suggested by the lines on member 29 in Fig. 6.

Actuating means for moving the jaw plates 26 and 27 toward each other on the converging series of roller bearings 24 and 25, comprise pistons 31 in cylinders 32. Abutments 33 may be arranged on the pistons 31, to engage the lower portions of the jaw plates 26 and 27, as best shown in Fig. 3. An extension 34 of reduced diameter underneath the piston 31 is disposed opposite an inlet 35 for air pressure. A flexible hose 36 is connected to the inlet 35. It is to be understood that each cylinder 32 has its own flexible connecting hose.

Means tending to maintain the jaw body 15 in adjusted positions comprises a helical spring 37 wound upon the shaft 14. The spring 37 abuts endwise against opposite, cup-shaped annular members 38 and 39, causing friction between the outer faces of the cup-shaped members and adjacent positions of the body 15 of the jaw member. A spline 40, urged in place by a screw 41 restricts rotary movement of the cup-shaped members 38 and 39.

In the operation of a stretching and shaping machine, having my present jaw members, any suitable table means 42 may be moved vertically between opposed jaws 15, which are arranged in lines parallel with each other. In Fig. 1 a metal sheet 43 has been indicated as being clamped at its ends by the jaw plates 26 and 27. Within the limits of the swinging movement of the jaw members 15 on the shafts 14, the jaw members may swing to any position, causing a straight pull on the metal sheet 43, when the table 42 is raised forcibly against the sheet 43. There may, of course, be a wide variety of shapes and sizes for the vertically movable table 42. The wavy line 44 in Fig. 1 indicates that the center portion of the sheet 43 and of the table 42 have been broken away.

After the ends or edges of the plate 43 are inserted between the jaw plates 26 and 27, air pressure is introduced into hose 36 to raise the piston 31, as shown in Fig. 3, causing said plate members to move toward each other on the roller bearings, to obtain a firm grip on the edges of the sheet by means of the roughened or knurled inserts 28 and 30. Such air pressure is maintained through the stretching operation of the machine.

Thereupon the center table 42 is move vertically by suitable means, stretching and shaping the metal sheet 43 to the desired degree and contour. After tension on the sheet 43 is released by lowering the center table 42, the air pressure in the hose 36 may also be released, permitting the portions of the sheet 43 within the jaw members, to be removed therefrom, due to the release of the piston 31 and of the jaw plates 26 and 27.

While I have illustrated and described what I now regard as the preferred embodiment of my invention, the construction is, of course, subject to modifications without departing from the spirit and scope of my invention. I, therefore, do not wish to restrict myself to the particular form of construction illustrated and described, but desire to avail myself of all modifications that may fall within the scope of the appended claim.

Having thus described my invention, what I claim and desire to secure by Letters Patent is:

Sheet anchoring means for a sheet stretching machine, comprising a stationarily mounted body member and a jaw member swingably mounted on said body member, and having sheet gripping means, said members having interlapping journal portions, a shaft journaled through said portions and forming the axis of swinging movement of said jaw member, one of the journal portions of the jaw member having a cavity, oppositely disposed cup-shaped friction elements surrounding the shaft within said cavity and having their outer surfaces frictionally engageable with the side walls of the cavity and their peripheral portions provided with notches adapted to align parallel to the axis of the shaft, a spring around the shaft in compression between and within said cup-shaped elements, and held thereby against displacement in a direction normal to the axis of the shaft, and a spline fixed on the body member opposite to, and entering, said cavity, and similarly projecting into the peripheral notches of the friction elements to thus lock the latter against rotation and preserve the spring against torsional disturbance during swinging movements of the jaw member.

MOSE D. RIPLEY.
